Mark Wedderburn

UNITED STATES PATENT OFFICE.

GEORGE GRONELL, OF NEW YORK, N. Y.

PADLOCK.

Application filed November 22, 1922. Serial No. 602,543.

To all whom it may concern:

Be it known that GEORGE GRONELL, a citizen of the United States, residing at New York, in the county of New York and State of New York, has invented certain new and useful Improvements in Padlocks, of which the following is a specification.

This invention relates to pad locks and has for its object to provide a keyless permanent lock which will consist only of a comparatively small number of parts which can be easily and readily assembled, thereby facilitating the manufacture of such locks in quantities and rendering the cost of manufacture very small.

My pad lock substantially consists of a solid steel disk formed with circumferential cavities, in one of which the shackle is pivotally and slidably mounted and in the other one of which the free toothed end of the shackle is adapted to be locked by engaging with a pinion meshing with a rack whose movement is limited by tumbler rings of a permutation lock accommodated in a central cavity of the steel disk.

My invention will be more fully understood by reference to the accompanying drawing in which similar reference characters denote corresponding parts and in which Fig. 1 is a front elevation of the padlock; Fig. 2 is an enlarged partial longitudinal section of said lock; Fig. 3 a cross section on line 3—3 of Fig. 2; Fig. 4 a cross section on line 4—4 of Fig. 1; Fig. 5 a cross section on line 5—5 of Fig. 2; Fig. 6 is an inner view of the boss; Figs. 7—9 show the tumbler rings of the permutation lock and the manner of their operation, and Fig. 10 is a modification of the construction of the tumbler rings.

In the drawing 10 denotes a solid circular disk made of steel and formed with a central circular cavity 11 and with circumferential cavities or bores 12, 13. 14 denotes the usual shackle. One end of said shackle is formed with an annular groove 14' and a longitudinal slot 14² movably engaged by a cross pin 15 passed through the disk 10 so that the shackle can be raised and swung around said pin. The other end of the shackle is toothed as at 14³ and fits in the other circumferential bore 13. Adjoining the latter is a circular cavity 15 in which

is mounted a pinion 16 which projects through a slot 15' terminating in the bore 13 so as to be capable of engaging the teeth 14³ of the shackle to lock the latter in closed position. On the opposite side the circular cavity has another slot 15² which terminates in a groove 17 in which is slidably mounted a short rack 18 whose teeth project into the circular cavity and mesh with said pinion 16. The rack 18 is formed at its inner end with a reduced portion 18' forming a tail adapted when the shackle is being unlocked and its toothed end moved outwardly from the bore 13 to pass into the central cavity 11. In the locked position the rack is held against downward displacement by means accommodated in said central cavity which constitute a permutation lock. According to the present embodiment of my invention this permutation lock comprises a plurality of split rings 19, 20 and 21 frictionally borne in the central cavity one upon the other. The rings are each radially recessed, as at 22, to impart resiliency thereto and are each formed with radial projections 19', 20', 21' of different width. The split portion 23 in each ring is such that the tail end 18' of the rack will be allowed to pass into the same. Rotatively borne in the cavity 11 is a boss in form of a disk 24 formed with a central axial extension 25 which at its end has an annular groove 25' to be engaged by a pin 26 passed through the body 10 and whereby the boss is secured in said cavity. Extending longitudinally from the inner face of the boss is a pin 27 of a length about equal to the total thickness of the three superposed rings 19, 20, 21 and serving to cooperate with their radial projections 19', 20', 21' so as to bring them in a position where the split portions 23 thereof will be in alignment with one another and with the inner open end of the groove 17 in which works the rack 18. In a narrow bore 28 of the body 10 a ball 29 is fastened by a spring 30 so as to partly project outwardly from said bore and in cooperation with an annular row of equidistantly arranged cavities 31 made in the inner face of the boss to form a clicking mechanism. The ball 29 while the boss is turned on its axis will snap successively in the different cavities 31 and when the parts are adjusted to the proper position

will arrest the boss against accidental displacement. The shoulders or projections 19', 20', 21' will be arranged in certain relations to the said cavities 31, so that by counting the clicks one can adjust the individual rings according to the particular combination.

An indicator finger 32 which may be adjustably fixed to project from the knob portion of the boss 24 will when brought into alignment with a mark on the outer face of the disk 10, indicate the position of the pin 27 operating the tumbler rings 19, 20, 21. By adjusting the finger 32 to a different position on the knob the combination chosen will be changed.

Projecting from the inner face of the boss is a circular rim 33 which also is formed with a circumferential groove 33' capable of engaging the tail end of the rack and with which the split portions 23 of the tumbler rings must be brought into alignment before the tail end of the rack will be allowed to move downwardly.

Instead of the rings 19, 20, 21 it is preferable to use the construction shown in Fig. 10, in which each ring is provided on its inner circumference with a number of radial incisions or grooves 34 substantially of square cross section. These grooves are equidistantly distributed and conform in spacing with that of the cavities 31 in the boss 24 and each serves to frictionally hold a pin 35 of square cross section. The pins 35 are placed in the grooves 34 in positions and numbers corresponding with the particular combination chosen.

The grooves 34 impart a certain resiliency to the rings so that the extra recess 22 made in the rings 19, 20, 21 can be dispensed with. With such construction of the rings the combination can be readily changed by varying the positions of the pins 35 in the grooves 34.

The mode of operation is as follows: Assuming that the shackle is closed. Then the rack 18 is in its elevated position shown in Fig. 2 and is unmovable, by reason of the openings 23 of the rings 19, 20, 21 being displaced relative to the open end of the groove 17 which bears said rack. Now to open the shackle the boss is first turned around until the finger 32 registers with a particular mark on the outer face of the boss. By this movement all rings are being consecutively brought into a certain position by the pin 27. Now the boss is turned a certain distance in one direction which distance is measured by the clicks produced by the ball 29 snapping into and passing out from the cavities 31. As a result one of the rings is adjusted with its opening 23 in alignment with the groove 17. Then the boss is turned in opposite direction a distance corresponding to a certain other number of clicks and

so on until all rings become located in alignment with the groove 17. The groove 33' in the rim 33 of the boss then being also in alignment with the openings 23 the rack becomes released, inasmuch as by pulling the shackle the pinion 16, will be allowed to turn feeding the rack 18 inwardly so that its tail end 18' will pass into the openings 23 of the rings and groove 33' of the boss. When passing the toothed end of the shackle into the bore 13 it will engage the pinion 16 and cause the rack to move in the opposite direction, releasing thereby the rings which on turning the boss will become displaced and form a stop locking the rack.

What I claim is:

1. A pad lock comprising a body portion, a vertically movable and pivotally supported shackle and having its locking end toothed, a pinion in said body capable of meshing with said locking end, a rack arranged parallel to said toothed end and meshing with said pinion diametrically opposite said toothed end and means for arresting said rack and thereby locking said pinion and shackle in closed position.

2. A pad lock comprising a body portion having a cylindrical cavity, a shackle slidably and pivotally supported in said body and having its locking end toothed, a pinion rotatively fitted in said cavity and capable of meshing with said toothed end, a rack parallel to said toothed end and meshing with said pinion diametrically opposite said toothed end, a movable member capable of arresting said rack, so as to lock the pinion and shackle in closed position and means for moving said member.

3. A pad lock comprising a body portion having a cylindrical cavity open at diametrically opposite sides, a shackle slidably and pivotally supported in said body and having its locking end toothed, a pinion rotatively fitted in said cavity and projecting with its teeth through one of said side openings to engage said toothed end, a rack parallel to the latter and meshing with the teeth of said pinion projecting through the opposite open end of said cavity, a rotary central member in said body capable of arresting said rack, so as to lock said pinion and shackle in closed position and means for turning said member.

4. A pad lock, comprising a solid circular disk having a central circular cavity and circumferential cavities, a shackle rotatively and slidably supported in one of said circumferential cavities and having its free end toothed, a pinion projecting into the other of said circumferential cavities to engage said toothed end of the shackle, a rack embedded in said body and meshing with said pinion and a permutation lock in said central cavity to lock said rack against movement.

5. In a pad lock, a shackle having its lock-

ing end toothed, a gear meshing with said toothed end, a rack meshing with said gear, and a permutable means for locking and unlocking said rack.

5 6. In a pad lock, a longitudinally movable shackle having its locking end toothed; a gear meshing with said toothed end, a rack meshing with said gear and permutable

means for controlling said rack to lock and unlock said gear.

In testimony whereof I affix my signature in presence of two witnesses.

GEORGE GRONELL.
